IGNITION SYSTEM

William W. Eitel, San Bruno, Calif., assignor to
 Eitel-McCullough, Inc., San Bruno, Calif., a
 corporation of California

Application October 11, 1943, Serial No. 505,885

5 Claims. (Cl. 123—148)

1

My invention relates to an ignition system for an internal combustion engine.

The broad object of my invention is to provide an improved ignition system embodying resonant means located in the combustion chamber and energized by a high frequency oscillator to produce a discharge.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawing:

Figure 1 is a diagrammatic view of an ignition system embodying the improvements of my invention; and

Figure 2 is a detail sectional view showing the portion of the engine cylinder containing the resonant means.

Figure 3 is a sectional view similar to Figure 2, showing a modified arrangement.

Figure 4 is a detail sectional view of an engine cylinder, disclosing another modified construction.

In terms of broad inclusion, my ignition system for an engine comprises resonant means in the combustion chamber adapted when energized to produce a discharge, a high frequency oscillator, means transferring energy from the oscillator to the resonant means, and means keying the oscillator to energize the resonant means in time with the operation of the engine.

In greater detail, and referring to Figures 1 and 2 of the drawing, my ignition system is shown more or less diagrammatically in conjunction with an engine having a cylinder 1 and associated piston 2. The cylinder has suitable intake and exhaust valves 3 ported into combustion chamber 4, and piston 2 is connected by a rod 6 to a crank shaft 7.

Resonant means are provided in the combustion chamber for producing a discharge when energized by a suitable oscillator 8. The type of resonant means shown in Figures 1 and 2 comprises a quarter-wave line made up of two parallel metallic rods 9 secured at one end to the cylinder wall and projecting into the combustion chamber. The higher the frequency the shorter the line would be, as will be readily understood by those skilled in the art. A shorted half-wave line of this kind, when properly energized, will have a potential node at the shorted end and a potential antinode at the open end. Under these

conditions a discharge can be made to occur across the gap at the open end of the line.

Oscillator 8 may be of any suitable type adapted to produce oscillations at the desired frequency. That shown comprises a pair of triodes 11 connected in a circuit having a tank coil 12 from which energy is transferred by a coil 13 feeding into a transmission line 14. The latter may be of any suitable type such as a concentric line comprising an outer tubular conductor 16 and an inner conductor 17. As shown in Figure 2, tube 16 is threaded into an aperture extending through the side wall of the combustion chamber and is plugged by a suitable insulator 18 through which inner conductor 17 projects. Conductor 17 is connected to the resonant line adjacent its shorted end.

Means are provided for keying the oscillator with pulses timed with the operation of the engine. This is done by discharging condenser 19 into the oscillator, the discharges being timed by a suitable switching device such as rotatable contactor 21 interposed in lead 20 from the condenser to the oscillator. Contactor 21 is rotated by a suitable drive means (indicated by dot and dash line 22) connected between crank shaft 7 and the contactor. The timing gears in drive means 22 are designed to close contactor 21 at the top of the compression stroke in accordance with the usual method of ignition timing.

Condenser 19 is charged by a suitable direct current supply such as a full wave rectifier tube 23 connected in circuit with a transformer 25.

In the modification shown in Figure 3 a tuned transmission line is employed comprising two parallel wires or rods 28 projecting into the combustion chamber through a suitable insulator 26 mounted on a threaded plug 27. The line section projecting into the combustion chamber is substantially $\frac{1}{4}$ wave in length, thus placing the potential node at the chamber wall. This being a tuned line it is understood that the line portions external the cylinder should be some multiple of a quarter-wave. Since the tuned line enters the combustion chamber at a potential node the insulation problems at this point are reduced to a minimum.

Figure 4 shows another modification in which the combustion chamber is shaped to form a resonant cavity having a gap 28 therein adapted to provide a discharge when the cavity is energized. Energy is transferred from the oscillator by a concentric line terminating in a loop 29 projecting into the resonant cavity.

I claim:

1. An ignition system for an engine having a combustion chamber, comprising resonant means in the chamber adapted when energized to produce a discharge, a high frequency oscillator, means transferring energy from the oscillator to said resonant means, and means keying the oscillator to energize the resonant means in time with the operation of said engine.

2. An ignition system for an engine having a combustion chamber, a resonant cavity formed by said chamber and having a gap therein adapted to produce a discharge when the cavity is energized, a high frequency oscillator, means transferring energy from the oscillator to the cavity, and means keying the oscillator to energize the cavity in time with the operation of said engine.

3. An ignition system for an engine having a combustion chamber, a resonant line projecting into the chamber adapted when energized to produce a discharge, a high frequency oscillator, means transferring energy from the oscillator to said line, and means keying the oscillator to en-

ergize the line in time with the operation of said engine.

4. An ignition system for an engine having a combustion chamber, a resonant line projecting into the chamber adapted when energized to produce a discharge, a high frequency oscillator, means transferring energy from the oscillator to said line, and means keying the oscillator to energize the line in time with the operation of said engine, the length of the line in said chamber being such as to place a potential node adjacent a wall of the chamber.

5. An ignition system for an engine having a combustion chamber, a resonant line projecting into the chamber adapted when energized to produce a discharge, a high frequency oscillator, means transferring energy from the oscillator to said line, and means keying the oscillator to energize the line in time with the operation of said engine, the length of the line in said chamber being substantially one-quarter wave length at the frequency of said oscillator.

WILLIAM W. EITEL.
